J. Woolley,

Edging Sheet-Metal.

Patented Mar. 16, 1831.

John Woolley of New York City.
Letters Patent.

The Schedule referred to in the Letters Patent and making part of the same containing a description in the words of the said John Woolley himself of his improvement in the Edging machine, or "French Horse" for turning the edges of tin, copper or sheet iron.

To all to whom these presents shall come. Be it known that John Woolley of the City, County and State of New York, have discovered a new and valuable improvement in the edging machine or "French Horse" and that the following is a full and exact description of the construction and operation of said improvement as invented by me. This invention is an improvement on the old edging machine or "French Horse" now in use for turning the edges of tin, copper or sheet iron, for the roofing of Houses &c. The construction is as follows. There is a suitable frame made of wood or other proper substance, and of tapering form towards the top. There is a horizontal bar secured to the uprights of this frame, and passing across the top of it. At the side of this bar are two others which are placed parallel with and below it and are moveable by means of guides on their ends, within the uprights of the frame. Secured on these bars are blades of steel or other proper substance, one of which is placed on the upper surface of each of the moveable bars, while the other is firmly fastened to the outer side of the permanent bar in a vertical position and projects below the surface of said bar. This blade is called the former, as the metal is bent over it by the action of the others. The tin or other substance is bent or turned in sheets, and is inserted under the former at back of the frame. The blade on the front bar being depressed to admit the edge between it and the former, when it is raised by means of a handle or lever inserted in the front bar, and thus turns up the edge of the tin at right angles. The operation is completed by turning up the opposite bar on

on which the sheet rests to a perpendicular position thus bending the edge over the Former. The sheet is then drawn out and vice versa. In order to bend the edges of a sheet of tin, it is first necessary that the corners be cut off, that the bend of one side may not interfere with the other. In this case when bent or turned by the old method, the extremities at each side are flattened on account of the angle of the blade or Former being square or circled longer above the edge. It is then necessary to open them by hand. The subscriber effectually removes this evil by performing the whole work of edging at one operation. This is effected by a small point or projection from each end of the Former, which penetrating into the extremity of the bend, when the end of the sheet has been cut off, preserves it equal throughout. On the upper surface of the moveable bar at the back of the Former are two grooves cut into it directly across, these are for receiving and preserving entire the edges of the sheet already turned while the other sides are acted upon by the former. The proceeding was invented before the 13th January 1831. The subscriber claims the privilege of varying or simplifying the construction of his improved Edging machine, so that a sheet of any length or any number of sheets, may be turned at the same operation. In this case the Former should be made as before mentioned and is to be firmly secured or otherwise fastened to a spring which is secured to a suitable bed or frame in such a manner that the former may rest flat upon it when pressed down, the spring on the back part serving to elevate it sufficiently for the insertion of the sheet. There is a corresponding blade which serves as a rest for the Former & is secured by means of screws or otherwise fastened to the front of the bed or frame, and comes in contact with the Former at right angles. There is hinged to the front of the frame a board of any length required, which has on its surface a corresponding blade. This board serves as a rest for the sheet when under the Former. There is a treadle attached by suitable contrivance to the under part of the former which is used to hold the sheet in its

place and prevent its slipping and is acted upon by the foot. (A lever to be worked by hand may be substituted when the work is light) The sheet of tin is inserted under the former which is then brought down upon it by means of the treadle the board is then to be turned completely over. (Similar to the shutting of a Book) carrying the sheet with it and thus turning or bending the edge to the required form. on the surface of this board should be grooves to admit the bent sides of the tin as before mentioned, it may also be used as a Gauge Board. The subscriber claims the sole privilege of constructing his improved Bending Machine of cast iron, Wood or any other suitable material, and further claims the exclusive right of applying his machine to the turning or bending the edges of sheets of Tin, Copper and iron or any other metal.

The subscriber also claims the privilege of forming metal roofs in such a manner that they effectually resist the driving of rain. This is done by inserting a small piece of metal (which has been previously bent by his machine) over each notch in the corners of the sheets, and are locked in with them on the roof. These pieces may be secured by nails and not being exposed to water are not so liable to rust. The old practice of driving nails through the sheet is thus dispensed with entirely.
